UNITED STATES PATENT OFFICE.

LOUIS C. H. GROEGER, OF CHICAGO, ILLINOIS.

ELECTRIC FURNACE AND METHOD OF OPERATION.

1,333,914.

Specification of Letters Patent. Patented Mar. 16, 1920.

Application filed April 5, 1918. Serial No. 287,695.

To all whom it may concern:

Be it known that I, LOUIS C. H. GROEGER, a citizen of the United States, residing at Chicago, in the county of Cook and State 5 of Illinois, have invented a new and useful Improvement in Electric Furnaces and Methods of Operation, of which the following is a specification.

This invention relates particularly to electric furnaces adapted to operate normally with electric current passing between upper electrodes and a wall or hearth contact and through the interposed charge, which preferably is fused by the arcing of the electric 15 current.

The primary object is to provide an electric furnace capable of being operated by several different methods, whereby improved results can be obtained. A further object 20 is to provide an improved general method of operation which possesses distinctive advantages.

The invention is illustrated in its preferred embodiment in the accompanying drawings, 25 in which—

Figure 1 represents a sectional view of an electric furnace in the preferred form, embodying the invention, the view being more or less diagrammatic, the furnace having 30 the electrodes adjusted to operate as a two-phase furnace; Fig. 2, a similar section, showing the furnace operating as a three-phase furnace, as, for example, in preliminarily heating the furnace; Fig. 3, a similar view showing the furnace operating 35 as a single-phase furnace, as where it is desired to "hold the heat," for example, while a chemical analysis of the metal is being made; Fig. 4, a similar view showing 40 a modification of the furnace operating as a two-phase furnace; and Fig. 5, a broken sectional view showing a modification of the hearth contact.

In the construction illustrated in Figs. 1 to 45 3, inclusive, A represents the body of the furnace provided with a heating, or melting chamber, A', and a hearth A²; B, B', a pair of side electrodes which are disposed opposite each other and extend through the side 50 walls of the furnace; B², an upper electrode which extends through the top wall of the furnace; C, C', the secondary coils of a transformer device, or pair of transformers, said coils having the terminals at one end 55 connected with a common, or neutral, conductor D, and having the other terminal con-

nected with conductors D', D²; E, E', the primary coils of the transformer device, or pair of transformers; F, a conductor, equipped with a switch F', adapted to connect adjacent terminals of the coils E and E'; G, a conductor, equipped with a switch G', said conductor G serving as a 50% tap for the coil E and an 86.6% tap for the coil E'; H, and H', conductors connected with the outside terminals of the coils E and E'; and H², a common, central, or return conductor connected with the conductor F; and I, J, and K, electric power supply lines adapted to be connected, by switches L, with 60 the conductors H, H², and H', respectively. 65

The conductors D, D' and D² are equipped with reactance coils M which may be used in starting operations, and may be cut out of the circuits by switches M' after stabilized 70 operation has been established.

The conductor D connects with the upper electrode B²; the conductor D' connects with the side electrode B; and the conductor D² connects with the side electrode B'. 80

The conductor D has a branch conductor 1 which leads to a terminal 1^a the conductor 1 being for use in two-phase operation of the furnace (as in Figs. 1 and 4).

The conductor D' has a branch conductor 85 2 which leads to a terminal 2^a, the conductor 2 being in use in single-phase operation of the furnace (in accordance with Fig. 3).

The hearth A² of the furnace is lined with suitable refractory material, which may be 90 relatively nonconductive when cold and conductive when hot, or which may be conductive when cold and hot.

The hearth is provided with a contact, or terminal N, with which is connected a conductor 3 which is equipped with a switch 3^a, which may serve to connect the conductor 3 with the branch conductor 1, or the branch conductor 2, as desired.

Any suitable construction may be employed, provision being made for keeping the electrodes insulated with respect to each other.

The side electrodes B and B' are tiltably mounted to enable them to be swung toward 105 and away from the charge, or bath, P; and the side electrodes are also longitudinally adjustable to enable their inner ends to be brought together and then separated in establishing the arc. Each of the side electrodes is preferably carried by an electrode clamp 4 mounted on a tiltable arm, or mem-

ber, 5, and adjustable toward and away from the furnace by mechanism 6, the details of which are unimportant and not shown.

The electrodes B and B' project freely 5 through slots 7 in the side walls of the furnace, and said electrodes are equipped with suitable cooling devices 8 which practically close the openings 7, and which may shift vertically somewhat, if necessary.

10 In the illustration given, the electrode-supports 5 are connected by pivots 9 to brackets carried by the side walls of the furnace; and the outer ends of the members 5 are equipped with racks 10 operated by 15 gear-trains 11 and electric motors 12.

The upper electrode B² is preferably disposed centrally, and is adjustable vertically, so that it may be lowered into contact with the inner ends of the side electrodes when 20 the latter are brought together, this arrangement enabling all of the electrodes to be brought together at their inner ends and then separated to establish the free burning three-phase arc Q, shown in Fig. 2. In 25 Figs. 1 and 4, the electrodes are shown in position for operating with a multiple two-phase arc Q'; in Fig. 3, the electrodes are shown in position for single-phase operation with a single arc Q² between the upper 30 electrode and the bath.

The electrode B² is preferably so mounted that it can be swung slightly in any direction, in adjusting the electrodes, so that they will meet properly at their inner ends. 35 The electrode B² is shown provided with a cooling device 13 and clamping and adjusting means 14 supported by brackets 15 mounted on the top of the furnace. No detail is shown, as any suitable means may 40 be employed.

Assuming the switches L to be closed, and assuming the switches M' to be open until the operation is established, and then closed, the preliminary heating of the furnace may 45 be effected, for instance, with the electrodes adjusted in the manner shown in Fig. 2. To secure a three-phase operation with the electrodes so adjusted, the switches 3^a and G' are left open and the switch F' is closed. 50 The current from the secondary coils thus passes through the neutral wire D and the wires D' and wires D², the three electrodes taking part in the operation, the furnace operating on the three-phase open delta 55 system. This same arrangement may be employed in burning in the hearth of the furnace, except that the side electrodes will be tilted downwardly so as to be as close as possible to the hearth, and the upper electrode being correspondingly lowered, whereby a three-phase free-burning arc is maintained close to the hearth.

Assuming the furnace to have been properly preheated (by a previous operation, 60 or operating in the manner described

above); the hearth will be conductive, even if composed of refractory material which is relatively non-conductive when cold. The furnace may then be operated as a two-phase furnace, with the electrodes adjusted 70 in the manner shown in Fig. 1. In this operation, the switch F' is left open, the switch G' is closed and the switch 3^a is on the contact 1^a, that is, connected with the branch-conductor 1. Thus, the conductive hearth 75 is in circuit with the conductor D leading to the neutral point of the secondary windings of the transformer device; and the current circulates through the side electrodes, 80 the bath, the conductor 3, and branch conductor 1 of the central conductor D.

This last described mode of operation is also employed in connection with furnace arranged as shown in Fig. 4.

From the description thus far given, it 85 will be understood that the first melting of the charge may be effected by means of a free-burning arc between the electrodes above the charge, and that the arc may then be established between the electrodes and 90 the bath, the current passing through the bath and through the hearth of the furnace. This overcomes the objections incident to establishing an arc between the electrodes and the charge at the outset, it being understood that the charge does not provide a sufficiently good conductive medium at the outset to enable the operation of the furnace to be readily stabilized. In passing current 95 through the charge, or through the upper 100 portion of the charge, as a path between the electrodes, more or less arcing will occur between the pieces which constitute the charge, causing fluctuations in the load and generally unsatisfactory operation.

105 The present invention enables these difficulties to be obviated, and enables a free-burning arc to be employed in the first or preliminary reduction of the charge, and then enables the arc to be transferred so as 110 to pass between the electrodes and the bath when the bath is in such condition as to properly conduct the current. Thus, the normal operation of the furnace can be carried on through the hearth with consequent 115 economy in the use of power, and with the resultant circulation of the molten metal, which tends to the production of uniform quality throughout the body of the metal. In case the furnace tends to become too hot, 120 or in the event that it is desired to "hold the heat," as, for instance, during the time required to make a chemical analysis, the side electrodes may be withdrawn, the upper electrode lowered, and an arc established 125 between the upper electrode and the bath in the manner illustrated in Fig. 3, the furnace now operating as a single-phase furnace and employing only the transformers E, C. In this operation, the switches F' and G' are 130

left open, and the switch 3^a is connected with the branch conductor 2. Thus, a circuit is established from the coils C through the branch conductor 2, the conductor 3, the 5 hearth, the bath, the electrode B², and the conductor D. It will be understood that this tends to economy of operation, as well as to the avoidance of overheating. Also, this provision enables the heat to be "held" while 10 chemical analyses are being made, so that the exact condition of the metal in the bath may be known.

In the modification shown in Fig. 4, the construction is similar to the construction 15 shown in Fig. 1, except that the body A³ of the furnace is formed without an opening in the top, and the upper electrode B² is omitted. Corresponding parts in Fig. 4 are indicated by a reference character shown 20 in Fig. 1.

In the modification shown in Fig. 5, the hearth A⁴ is shown provided with a contact, or electrode, A', of carbon or metal. This form of electrode may be employed either 25 in the construction shown in Fig. 1 or in the construction shown in Fig. 4.

From the description given, the advantages of the improved furnace will be readily understood by those skilled in the art. 30 Any suitable source of power supply may be employed; and any suitable transformer means may be employed, where transformer devices are desired.

With the transformer device, the electric 35 circuits and the switches arranged as illustrated, the furnace may be operated as a single-phase furnace, a two-phase furnace, or a three-phase furnace; and the capability of the furnace for ready conversion to these 40 different methods of operation possesses distinct advantages, many of which have been pointed out. It will be understood, however, that a great variety of modifications of the transformer devices and connections 45 may be made, without departing from the spirit of my invention.

The foregoing detailed description has been given for clearness of understanding only, and no unnecessary limitation should 50 be understood therefrom, but the appended claims should be construed as broadly as permissible, in view of the prior art.

What I claim as new, and desire to secure by Letters Patent, is:

55 1. In an electric furnace, the combination of a heating chamber having a hearth terminal, a plurality of co-acting side electrodes extending toward each other from the sides of the furnace and so disposed above the bath as to enable an arc to be established directly between their inner ends, said electrodes being tiltable; adjusting means adapted to vary the tilt of said electrodes, and means whereby circuits may be established with an arc directly between the elec-

trodes or with an arc between the electrodes and the bath with the circuit completed through the hearth terminal.

2. In an electric furnace, the combination of a heating chamber having a hearth terminal, a pair of tiltably mounted side electrodes disposed opposite each other and adapted to have their inner ends brought together and then separated to establish a direct arc between the electrodes, a source 70 of electric current, and means whereby the furnace may be caused to operate with an arc directly between said electrodes, or with an arc between said electrodes and the bath, with the circuit completed through the 75 hearth terminal.

3. In an electric furnace, the combination of a heating chamber having a hearth terminal, a plurality of side electrodes so disposed above the bath as to enable an arc to 80 be established directly between their inner ends, an upper electrode extending through the top wall of the furnace and so disposed and mounted that its inner end can be brought into contact with the inner ends of 85 the side electrodes, a source of electric energy, and means whereby a free-burning arc may be established between the side electrodes and upper electrode and whereby an arc may be afterward established between 90 the side electrodes and the bath with the circuit completed through the hearth terminal. 95

4. In an electric furnace, the combination of a heating chamber having a hearth terminal, a plurality of side electrodes so disposed 100 above the bath as to enable an arc to be established directly between their inner ends, an upper electrode extending through the top of the heating chamber and adapted to have its inner end brought into contact with the inner ends of said side electrodes, a source of electric energy, and connections and switches, whereby the furnace may be operated with an arc between all three electrodes, or with an arc between the side electrodes 105 and the bath, or with an arc between the upper electrode and the bath.

5. In an electric furnace, the combination of a heating chamber having a hearth terminal, a plurality of side electrodes extending through the side walls of said heating chamber and adapted to have their inner ends brought substantially into contact, an upper electrode extending through the top wall of the furnace and adapted to have 115 its inner end brought substantially into contact with the inner ends of said side electrodes, and transformer means, circuits and switches, whereby said three electrodes may operate with a free-burning arc between 120 them in a three-phase system, or whereby said side electrodes may operate with an arc between them and the bath with the circuit completed through the hearth terminal 125 on a two-phase system, or whereby said up- 130

- per electrode may operate with an arc between it and the bath with the circuit completed through a hearth terminal in a single-phase system.
5. In an electric furnace, the combination of a heating chamber having a hearth terminal, three electrodes disposed above the bath and adapted to have their inner ends brought substantially into contact to enable an arc to be established, two of said electrodes projecting toward each other from the sides of the furnace and the third electrode depending through the top of the furnace, and transformer means, connections and switches, whereby the furnace may be operated with a free burning arc directly between the electrodes, or may be operated with an arc between the side electrodes and the bath, with the circuit completed through the hearth terminal.
10. In an electric furnace, the combination of a heating chamber having a hearth terminal, three electrodes disposed above the bath and adapted to have their inner ends brought substantially into contact to enable an arc to be established, and transformer means, connections, and switches, whereby the furnace may be operated as a three-phase furnace, a two-phase furnace, or a single-phase furnace.
15. In an electric furnace, the combination of a heating chamber having a hearth terminal, a pair of tilttable electrodes disposed opposite to each other and projecting through the side walls of the furnace, an adjustable upper electrode depending through the top wall of the furnace, transformer means having a pair of secondary coils, a conductor connecting one terminal of each of said coils with said upper electrode, conductors connecting the other terminals of said coils with the side electrodes, said first-named conductor having a branch conductor connected therewith, a conductor connected with the hearth terminal, and means for connecting said last-named conductor with said branch conductor.
20. In an electric furnace, the combination of a heating chamber having a hearth terminal, a pair of tilttable electrodes disposed opposite to each other and projecting through the side walls of the furnace, an adjustable upper electrode depending through the top wall of the furnace, transformer means having a pair of secondary coils, a conductor connecting one terminal of each of said coils with said upper electrode, conductors connecting the other terminals of said coils with the side electrodes, said first-named conductor having a branch conductor connected therewith, a conductor connected with the hearth terminal, a branch conductor leading from one of the conductors connected with a side electrode, and a switch adapted to connect the conductor of said hearth terminal with either one of said branch conductors.
25. In an electric furnace, the combination of a heating chamber, a pair of pivotally-mounted arms disposed at opposite sides of said chamber, adjustable side electrodes mounted on said arms and extending through the side walls of the furnace, mechanism for turning said arms about their pivots to vary the inclination of said side electrodes, and a source of electric energy connected with said electrodes.
30. In an electric furnace, the combination of a heating chamber, a pair of pivotally-mounted arms disposed at opposite sides of said chamber, adjustable side electrodes mounted on said arms and extending through the side walls of the furnace, racks depending from said arms, motor devices geared to said racks, and a source of electric energy connected with said electrodes.
35. In an electric furnace, the combination of a heating chamber provided with a hearth contact, a pair of swinging adjustable side electrodes located directly opposite each other, an adjustable upper electrode depending through the top wall of the heating chamber, a source of electric energy, and means whereby either said side electrodes or said upper electrode may be caused to operate with an arc through the bath, with the circuit completed through said hearth terminal.
40. In an electric furnace, the combination of a heating chamber provided with a hearth contact, a pair of swinging adjustable side electrodes located directly opposite each other, an adjustable upper electrode depending through the top wall of the heating chamber, a source of electric energy, and means whereby said three electrodes may be caused to operate with an arc directly between them as a three-phase system, or whereby said side electrodes may be caused to operate with an arc between them and the bath, with the circuit completed through the hearth terminal, or whereby said upper electrode may be caused to operate with an arc to the bath and with the circuit completed through said hearth terminal.
45. The method of heating an electric furnace which comprises: causing an arc directly between the inner ends of three electrodes; then establishing a circuit between the inner ends of two of said electrodes and the bath to the hearth and operating with arcs between said two electrodes and bath.
50. The method of heating an electric furnace which comprises: causing an arc directly between the inner ends of three electrodes; then establishing a circuit between the inner ends of two of said electrodes and

trodes and the bath to the hearth, operating with arcs between said two electrodes and bath and then withdrawing said two electrodes and operating with an arc between the third electrode and the bath with the circuit completed through the hearth.

16. The method of heating and regulating the heat of a furnace which comprises:

operating with an arc between the inner ends of two oppositely disposed electrodes and the bath with the circuit completed through the hearth; and then withdrawing said electrodes and operating with an arc between a third electrode and the bath with the circuit completed through the hearth.

LOUIS C. H. GROEGER.
